UNITED STATES PATENT OFFICE.

GEORGE A. BUDGE, OF BERKELEY, CALIFORNIA, ASSIGNOR, BY MESNE ASSIGNMENTS,
TO AERIAL AMUSEMENT CONSTRUCTION COMPANY, OF PHOENIX, ARIZONA TERRI-
TOBY, A CORPORATION OF ARIZONA TERRITORY.

AMUSEMENT APPARATUS.

972,750.

Specification of Letters Patent. Patented Oct. 11, 1910.

Application filed December 27, 1909. Serial No. 535,146.

To all whom it may concern:

Be it known that I, GEORGE A. BUDGE, a citizen of the United States, residing at Berkeley, in the county of Alameda and State of California, have invented new and useful Improvements in Amusement Apparatus, of which the following is a specification.

My invention relates to an apparatus which is designed for amusement purposes.

It consists of aeroplanes, an elevated guide-way, and propelling mechanism.

It also comprises combinations of parts and details of construction which will be more fully explained by reference to the accompanying drawings, in which—

Figure 1 is a general perspective view of the apparatus. Fig. 2 is a side sectional elevation. Fig. 3 is a transverse section.

It is the object of my invention to provide an apparatus for the amusement of patrons, said apparatus simulating an aeroplane or flying machine, and illustrating the movements of such apparatus; and the combination therewith of a means for making the apparatus perfectly safe to inexpert users.

A—A represent the planes of a bi-plane apparatus, one being superposed above the other. It will however be understood that a monoplane, or other variation in the construction may be employed, without materially altering the character of my invention. These planes are mounted upon a casing 2.

The central portion of the apparatus may be provided with any desired number of seats, 4, for passengers, and a motor 5 may be located beneath one of the seats, or within the casing 2.

The shafts are journaled across the lower part of the frame or casing upon which may be mounted wheels 6. These wheels are preferably flanged, and are adapted to run upon a mono-rail 7 which is supported upon any suitable structure as 8, and may be elevated at any desired distance above the ground by suitable posts or standards 9. At a point sufficiently below the rail 7 may be located a channel iron rail or rails 10, and braces 11 extend diagonally from the lower plane A converging to a point contiguous to the rails 10. Antifriction wheels or rollers 12 are journaled in the lower part of this bracing structure, and are adapted to run

upon the guide rails 10. It will be understood that these rails may be plain, and the 55 wheels grooved, with equal effect to the rail construction above described, the object being in any case to steady the apparatus, and prevent its overturning.

Upon the shaft of one of the wheels 6 is 60 mounted a gear 13 which is engageable with the motor, either by means of a worm or screw 14, or by other suitable driving gear-chain or belt, and through this the power of the motor is transmitted to rotate the wheel 65 or drum 6 which rests upon the track. It will be understood that if more tractive power is required, as in case the track is designed to run uphill at certain points of its course, the wheels may be connected, or one 70 of the wheels may be geared or corrugated, or otherwise constructed to have sufficient adhesion to the track for propelling purposes.

In order to heighten the illusion, I have 75 shown a horizontally disposed guide plane 15, and if desired a vertically swiveled guiding plane may also be connected. The plane 15 is suitably connected with a steering-post 16, and by means of a hand-wheel 17 located 80 convenient to the front seat, one of the passengers in this seat may use the wheel to move the plane of planes, through the worm-gear 18—19.

The trackway may run upon a level, or it 85 may be sinuous, rising and falling to imitate the movements which would take place with a poised aeroplane.

The current to drive the motor may be taken from one of the guide rails 10, this 90 being insulated from the frame-work, and may be grounded back on the monorail.

Having thus described my invention, what I claim and desire to secure by Letters Patent is—

1. An amusement apparatus consisting of 95 aeroplanes having bearing-wheels, a track upon which said wheels are guided and movable, a motor, and intermediate connections by which power is transmitted to one 100 or more of the guiding wheels, seats carried upon the apparatus, and a guiding plane and controlling wheel connected therewith.

2. An amusement apparatus including an 105 elevated mono-rail, an aeroplane having centrally located, flanged bearing-wheels

adapted to travel upon the rail, and seats carried by the apparatus, turnable guiding planes and steering-post and wheel connected therewith, and guide rail located below the bearing-rail, convergent braces extending from the plane toward said guide rail, and rollers carried by the brace frame adapted to travel against the rail, a motor mounted in the body of the machine, and intermediate mechanism by which power is

transmitted from the motor to the bearing wheels.

In testimony whereof I have hereunto set my hand in the presence of two subscribing witnesses.

GEORGE A. BUDGE.
